(57) **CLAIM**

The ornamental design for a nozzle with lateral spray as shown and described.

DESCRIPTION

FIG. 1 is a front perspective view of a nozzle with lateral spray showing our new design;

FIG. 2 is a front elevational view thereof;

FIG. 3 is a rear elevational view thereof;

FIG. 4 is a right elevational view thereof;

FIG. 5 is a left elevational view thereof

FIG. 6 is a top plan view thereof;

FIG. 7 is a bottom plan view thereof; and,

FIG. 8 is a side perspective view thereof.

The dash-dash broken lines shown in the drawings illustrate portions of the article, the dot dash dot broken lines illustrate the bounds of the claim; all broken lines form no part of the claimed design.

1 Claim, 8 Drawing Sheets
